UNITED STATES PATENT OFFICE.

FREDERICK G. NIEDRINGHAUS AND WILLIAM F. NIEDRINGHAUS, OF ST. LOUIS, MISSOURI.

HINGE FOR VESSELS OF ENAMELED IRONWARE.

SPECIFICATION forming part of Letters Patent No. 286,628, dated October 16, 1882.

Application filed June 4, 1883. (No model.)

To all whom it may concern:

Be it known that we, FREDERICK G. NIEDRINGHAUS and WILLIAM F. NIEDRINGHAUS, residents of St. Louis, Missouri, have made a new and useful Improvement in Hinges for Vessels of Enameled Ironware, of which the following is a full, clear, and exact description, reference being had to the annexed drawings, making part of this specification, in 10 which—

Figure 1 is a view in perspective of a vessel having the improvement; Fig. 2, a plan of the lid; Fig. 3, a vertical section of the lid; Fig. 4, a vertical section of the upper end of the body of the vessel; Fig. 5, a view in perspective of the hinge; Fig. 6, a vertical section of that portion of the construction immediately connected with the hinge, and Fig. 7 a vertical section of the central portion of the lid.

20 The same letters denote the same parts.

Our aim is to provide a neat and durable hinge for vessels of enameled sheet-iron ware.

A represents the body of the vessel, and B its lid or cover. These parts are coated with 25 an enamel—such as used, for instance, upon the granite-ironware. Prior to the application of the enamel to the cover the cover is perforated at b, Fig. 3, to receive the rivet or rivets used to fasten the hinge-strap.

30 C represents the hinge-strap. It is folded

around the wire a, (that usually encircles the top of the body A,) and its ends c c, in place of passing up through the cover B, are both laid against the under side of the cover. Rivets D D are then passed through the perforations b in the cover and through the perforations c' c' in the strap, and the ends c c thereby riveted to the cover, substantially as shown in Fig. 6. The strap is of a material to which solder attaches, in case it is desirable to secure 35 the rivets by means of solder—such as at d, Fig. 6. The rivets, however, may be headed at either end thereof in any suitable manner.

A', Fig. 6, represents the enamel coating upon the body A, and B' represents the enamel coating upon the cover B. The ends c c may be laid against the upper side of the cover.

We claim—

The combination of the enameled body A, 50 the enameled lid or cover B, the strap C, and the rivet or rivets D D, the strap ends c c being laid against the lid or cover and riveted thereto, substantially as described and shown.

F. G. NIEDRINGHAUS.
WM. F. NIEDRINGHAUS.
